UNITED STATES PATENT OFFICE

126,640

DESIGN FOR A CASING FOR SOUND APPARATUS

David C. Rockola, Chicago, Ill., assignor to Rock-Ola Manufacturing Corporation, Chicago, Ill., a corporation of Delaware

Application February 5, 1941, Serial No. 98,751

Term of patent 3½ years

To all whom it may concern:

Be it known that I, David C. Rockola, a citizen of the United States, residing at Chicago, in the county of Cook and State of Illinois, have invented a new, original, and ornamental Design for a Casing for Sound Apparatus, of which the following is a specification, reference being had to the accompanying drawing, forming a part thereof.

Fig. 1 is a perspective view of a casing for sound apparatus showing my new design, the rear wall of the casing being plain and the opposite sides being similar; and

Fig. 2 is a side elevation of the casing.

I claim:

The ornamental design for a casing for sound apparatus, substantially as shown and described.

DAVID C. ROCKOLA.
